(57) **CLAIM**

The ornamental design for an all terrain vehicle front fairing, as shown and described.

DESCRIPTION

FIG. 1 is a front-left perspective view of an all terrain vehicle front fairing according to our design;

FIG. 2 is a rear-left perspective view thereof;

FIG. 3 is a top view thereof;

FIG. 4 is a left side view thereof;

FIG. 5 is a right side view thereof; and,

FIG. 6 is a front view thereof.

Where included, the broken lines showing environment or structure are for illustrative purposes only and form no part of claimed design.

The portion of the all terrain vehicle front fairing which are not shown in the drawing form no part of the claimed design.
